WINDOW CLEANING DEVICE

Clarence H. Caldwell, Oak Park, Ill.

Application July 31, 1933, Serial No. 683,004

3 Claims. (Cl. 15—232)

This invention relates to window cleaners and will be described as incorporated in a device suitable for cleaning the outside of a window while the operator remains inside the building.

5 An object of this invention is the provision of a device of simple construction, containing relatively few parts, which device is easily operated and efficient and which is economical to manufacture.

10 Another object is the provision of such a device by which the outside of a window may be cleaned during cold weather without the necessity of keeping the window open an appreciable amount during the cleaning operation.

15 A further object is the provision of such a device capable of being applied to a window and operated to clean the window even though a screen may be secured adjacent the outer side of the window.

20 Other objects and advantages of this invention will become apparent from the following detailed description with reference to the accompanying drawings.

On the drawings:

25 Figure 1 is a fragmentary section through a window frame and window, illustrating my invention associated therewith for the purpose of illustrating the method of operation.

Figure 2 is a fragmentary section similar to 30 Figure 1 illustrating a further step in the operation of my invention.

35 Figures 3 and 4 are fragmentary vertical sections through a portion of that illustrated in Figure 5 and showing devices for holding a window sash in position relative to another window sash, during the process of cleaning the window.

Figure 5 is a fragmentary elevation of a window with parts broken away, illustrating the locking and holding devices shown in Figures 3 and 4.

40 Figure 6 is a top plan view of the improved window cleaning device incorporating this invention.

Figure 7 is a longitudinal section taken on substantially the line VII—VII of Figure 6.

45 Figure 8 is a similar longitudinal section taken on the line VIII—VIII of Figure 6.

As shown on the drawings:

It is a well recognized fact that many dangers attend the cleaning of windows on the outer sides 50 where it is necessary to stand or sit on the outside sill or lean out of the window in order to perform the cleaning operation. Although various forms of belts and harnesses have been provided for the safety of persons cleaning the outer sides of windows, it is nevertheless exceedingly

dangerous as well as inconvenient and at times exceedingly awkward.

The window cleaning device comprising this invention is illustrated in Figures 1 and 2 in association with a window to be cleaned. A window frame designated generally by numeral 5 is provided with stops or guiding members 6, 7, and 8 which are adapted to guide the window sashes 9 and 11 in their vertical movements to various positions within the window frame. A screen sash 12 having fixed thereon a screen 13 is illustrated in a position adjacent the outer side of the lower window sash when the window is closed. The window sashes 9 and 11 are provided with panes of glass 14 and 15 respectively.

The window cleaning device illustrated in Figures 6, 7, and 8, comprises a window cleaning element 21 which may be formed of cloth, chamois or other suitable material and is adapted to be readily replaced and renewed by a different washing or wiping element as may be desired. In Figures 7 and 8 the cleaning element 21 is shown to be of double thickness and as stretched over the ends of and extending beyond the lateral edges of a backing plate 22, preferably of sheet metal and having laterally extending corrugations 23 and downwardly deflected end portions 24 which serve to normally hold the cleaning element away from the body of the backing plate 22 a sufficient distance to permit yielding of the cleaning element and to effectively prevent undue suction or vacuum effect between the cleaning element and the window which may have a tendency to prevent effective operation of the cleaning device over the surface of the window.

As best illustrated in Figure 6, the end portions 26 and 27 of the cleaning member 21 are provided with eyelets 28 and 29 for assisting in the attachment of the cleaning member to the backing plate 22. The backing plate 22 may be firmly secured to a supporting block 31 by suitable screws 32 or the like. Although the backing block may consist of a single element if desired, it is shown in the drawings as comprising initially separate blocks 31 and 33, which may consist of wood or suitable molded material of relatively light weight, which are preferably permanently secured together by glue or in some other manner along their adjacent surfaces indicated by the line 35 such that the two blocks are in substance and in operation a single support block for the backing member 22. The backing member 22 is provided with screws 36 having heads of a size adapted to pass through the eye-

lets 28, upon which the eyelets may be disposed as illustrated in Figure 7, for holding the end 26 of the cleaning element in position. It will be understood that the use of the screws 36 are not essential, and that portions of metal may be formed directly from the body of the backing plate 22 to serve the same purpose if desired. At the opposite end of the supporting block, a laterally extending locking element 38 is illustrated which is provided with hooks 39 on each end which are adapted for engagement through the eyelets 29, for holding the end 27 of the cleaning element firmly in position. The locking member 38 is illustrated as consisting of a wire, 15 extending cross-wise of the plate and having a bent handle portion 41 disposed to lock the locking member for securing or releasing the cleaning member 21 to or from the plate. The handle portion 41 is formed as a loop of the wire of which the locking member 38 is constructed, and is disposed to be adjacent a side of the block 31. The handle 41 may be oscillated about the body of the locking member as a center for engaging the hooks 39 with the eyelets 29 in one end of the 20 cleaning member or for disengaging the hooks 39 from such eyelets to enable replacement or removal of the cleaning member. The handle is normally maintained in locking position by engagement under the head of a screw or the like 25 30 43 which projects from the side of the block 31 adjacent the handle 41 for holding the handle to maintain the locking element in locking position, as illustrated in Figure 7. In order to release the handle 41 and disengage the hooks 39 from the eyelets 29, the handle 41 must be forcibly rotated in clockwise direction, as observed in Fig. 7, to place the hooks 39 in a position for the removal of the eyelets 29, permitting the cleaning element 21 to be removed from the backing plate. 40 The block 33 is provided with means for securing an actuating member 45 thereto for moving the device over the surface of a window to be washed. The actuating member 45 may be formed of any suitable material but for purposes 45 of illustration there is shown a fabric strap which is flexible and is preferably waxed to minimize friction on the window sash. The member 45 may be provided with a buckle 47 as illustrated in Figure 2, for adjusting the length thereof. 50 The member 45 is also provided with weighted ends as indicated at 67 and 68 which serve to assist in manipulating the ends to drop them between the window sashes when a wind is blowing, and with snap fasteners or the like 46 which 55 cooperate with corresponding fastening elements 49 on a strap 52 which is fixed to the block 33 by nails 51 illustrated in Figure 8. The ends of the member 45 may also be secured together by a suitable snap fastener consisting of coengaging elements 46 and 49.

In Figures 3, 4, and 5, there is illustrated devices for holding the window sashes in fixed relative position during the cleaning operation. These devices preferably comprise a resilient block 61 disposed between adjacent portions of the sashes 9 and 11, preferably adjacent one edge of the window, and an adjustable link member 62 preferably disposed adjacent the opposite edge of the window in order to permit unobstructed 65 operation of the actuating element 45 during the cleaning operation. The link 62 preferably consists of a shank portion having one rigid end formed in the shape of a hook as illustrated at 63, and an adjustable hook member 64 on the 70 other end. 75

In the operation of my improved device, for example in the cleaning of the upper sash of a window, when a screen is employed, adjacent the lower sash, the ends of the actuating member 45 are first passed downwardly on opposite sides of the upper sash, with the upper sash in a central position in the frame. The lower ends of the member 45 are then snapped together by the snap fastener 46, and the member 45 is moved around the sash until the ends are in a position above the sash. With the ends in this position, the cleaning device may be secured into position by the snap fasteners indicated in Figure 1. The cleaning device is passed outwardly over the top of the sash and the sash moved upwardly to the 15 position illustrated in Figure 2 with the top of the sash clearing the top of the window frame and being held in position by means of the securing members shown in Figures 3 and 4 such that the actuating strap may be freely operated around the top and bottom of the sash. The actuating element 45 is then moved up and down in a manner to reciprocate the cleaning element over the surface of the window pane to be cleaned without necessitating the operator's going outside of the window, and without keeping the window open an appreciable distance during the cleaning operation.

It will be appreciated by those skilled in the art that this invention is susceptible of various forms and modifications without departing from the principle of the invention herein set forth and it is desired that the patent to be granted hereon shall not be restricted in any manner except as necessitated by the prior art and by the scope of the appended claims.

I claim as my invention:

1. In a window cleaning device, a supporting block, a backing plate secured to said block, said plate having a projection on its top side, a window cleaning element adapted to be applied against the bottom side of said plate and having an end adapted for engagement with said projection, a locking member rockably carried by said device for hooking engagement with the other end of said cleaning element when rocked in one direction and when rocked in the opposite direction adapted to tension said cleaning element in position on said plate, a portion of said member being deflected out of the direction of the length thereof and between its ends to provide a handle, and a projection on said block engaged by said handle when said member is rocked to tension said element to prevent accidental release of said element. 55

2. In a window cleaning device, a member adapted to be moved up and down against a window pane and adapted to support and carry a cleaning element, said member including a block, a backing plate secured to said block, said backing plate having greater length and width than said block to facilitate giving access to the margins and corners of the window to be cleaned, said backing plate having a projection on its top side, a cleaning element adapted to be applied against the bottom of said plate and having an end adapted for engagement with said projection, a locking member comprising a piece of wire with its ends bent to form hooks and a portion intermediate its ends deflected out of the direction of the length thereof to provide a handle rockably carried by said member for hooking engagement with the other end of said cleaning element when rocked in one direction and when rocked in the opposite direction adapted to tension said clean- 70 75 75

ing element in position on said plate, a projection on said block engaged by said handle when said rocking member is rocked to tension said element to prevent accidental release of said element, a flexible actuating strap for said member, and cooperatively engageable snap fastener elements on said block and strap whereby said member may be quickly applied to and removed from said strap.

10 3. A window cleaning device comprising a

cleaning element adapted to be moved against the outside of a window pane from the inside of the window, and a flexible tape engaging against the top and bottom rails of the window sash without intervening anti-friction means and connected to said element for actuating it, said tape being waxed to minimize friction as it is drawn back and forth in use in direct contact with the sash rails.

CLARENCE H. CALDWELL. 10.
